UNITED STATES PATENT OFFICE

GODFREY A. MUELLER, OF POINT PLACE, OHIO, ASSIGNOR TO THE DE VILBISS COMPANY, OF TOLEDO, OHIO, A CORPORATION OF OHIO

SPRAY HEAD

Application filed April 21, 1927. Serial No. 185,386.

This invention relates to devices for spraying surface coating materials, and particularly to spray-heads therefor, of the supplemental air discharge or fan spray type; and has for its object the provision of a spray-head of this character having certain novel and advantageous features of construction.

The invention is fully described in the following specification and one embodiment thereof illustrated in the accompanying drawings, in which,—

Figure 1 is a central longitudinal section of a spray-head embodying the invention. Fig. 2 is a front end elevation thereof. Fig. 3 is a side elevation of the spray-head showing the supplemental air control parts in separated relation and with the valve member partly broken away. Fig. 4 is an inner end elevation in assembled relation of the spray-head parts shown in Fig. 3. Fig. 5 is a similar view thereof with the valve member removed, and Fig. 6 is a fragmentary cross-section of a slightly modified form of the valve ring.

Referring to the drawings, 1 designates the inner or material discharge nozzle of the spray-head, which nozzle, in the present instance, is integral with and projects centrally from the forward end of a body part 2 adapted to be attached to a gun or holder, not shown, so that said body and nozzle form a rigid part thereof. The nozzle throat 3 extends back through the body part 2 and is intended to have communication with a source of supply of material to be sprayed. The body 2 is radially enlarged with respect to the nozzle and, in the present instance, forms an annular forwardly facing shoulder 4 around the inner end of the nozzle 1 in concentric relation thereto, and is undercut to form an inwardly tapering seat. An annular shoulder 5 is provided on the body part at the rear of the shoulder 4 for receiving the thrust of the inturned flanged end of a union nut 6. An outer or air discharge nozzle 7 encircles the nozzle 1 and has its throat cooperating with the nozzle 1 to form an air space 8 therebetween and is restricted at its outer end to cooperate with the restricted discharge end of the nozzle 1 to form a discharge

orifice 9 therearound, as well understood in the art. The rear end of the nozzle 7 seats against the body shoulder 4 and is held thereto by the union nut 6, which, in the present instance, has threaded engagement at its forward end portion with the external rear end portion of said nozzle. It is evident that the discharge of air from the nozzle orifice 9 in encircling relation to the material discharging from the inner nozzle 1 will effect a breaking up of the material in spray form. Nothing novel is claimed for this feature of the spray-head. The air space 8 between the nozzles is in communication, in the present instance, with a source of air pressure supply through one or more passages 10 in the body part 2.

The outer nozzle 7 is provided at its forward end at opposite sides of its axis with ears 11, each having a supplemental air discharge passage 12 therethrough with its discharge end disposed at an angle to meet the stream discharging from the other passage 12 at a point in axial alignment with the discharge orifices of the nozzles, so that the spray stream discharging from the nozzle will be flattened or broadened into fan spray form by the opposing discharge of air thereagainst from the passages 12.

The feature of the present invention resides in the control for the air discharging from the supplemental air discharge passages 12, so that such air may be entirely shut off or regulated as to volume and pressure according to the particular requirements. For this purpose the nozzle 7 is provided around its forward end portion with a rearwardly facing conical seat 13, having an arcuate groove 14 therein and extending partially around the same. This groove has the supplemental air discharge passages 12 leading therefrom. One or more passages 15 extend from the conical surface 13 inwardly through the body of the nozzle 7 in communication at their inner ends with the air supply space 8 between the two nozzle members.

A ring valve 16 having an inner conical surface complimentary to the conical surface 13 is mounted for turning movements on said latter surface and is adapted to cover both

the groove 14 and the passages 15 in said surface. An arcuate groove 17 is provided partially around the interior of the valve member 16 and is adapted to register with the passages 15 when the valve member is seated on the conical surface 13 and is turned in proper position. The groove is adapted to span the space between the passages 15 and incut 18, or lateral enlargement of the groove 14 so that air may be supplied from the passages 15 through the valve groove 17 to the groove 14. When the valve groove 17 is turned out of communicating register with the passages 15 and incut 18, the supply of air to the supplemental discharge passages 12 is entirely shut off. The groove 17 is preferably gradually tapered in depth from one end to the other thereof, as shown in Fig. 6, so that an increasing volume of air 20 may be permitted to enter the groove from the passages 15 by a turning of the valve member.

The valve 16 is held yieldingly seated on the conical surface 13 for turning movements thereon by a nut 19 and interposed spring washer 20. The nut 19 is threaded on the threaded inner end portion of the nozzle 7.

It is apparent with this form of supplemental air control that the valve means is carried entirely by the main air nozzle 7 for turning movements therewith, so that a turning of such nozzle to vary the plane of broadening of the spray will not affect the adjustment of the valve 16; and also that the valve 16 may be turned to either open or close the supplemental air discharge passages or to regulate the volume and pressure of air therefrom without affecting the adjustment of the nozzle 7.

I wish it understood that my invention is not limited to any specific construction, arrangement or form of the parts, as it is capable of numerous modifications and changes without departing from the spirit of the claims.

Having thus described my invention, what I claim as new and desire to secure by Letters Patents is:

1. A spray-head having an annular external surface, an arcuate groove therein extending part way around the same and with supplemental air discharge passages leading from said groove, said surface also having air supply passages in communication with an air supply source, and a ring valve mounted on said surface and adapted by a turning thereof to control the communication between said supply passages and groove.

2. A spray-head having an external rearwardly facing conical surface with a circumferentially extending groove therein and with supplemental air discharge passages leading from said groove, said surface also having passages adapted to have communi-

cation with an air pressure supply source, a ring valve having an internal conical surface complementary to and seating on said first conical surface and covering said groove and supply passages, said valve having provision for controlling the supply of air from said passages to said groove upon a turning of the valve.

3. A spray head having supplemental air discharge passages adapted to have communication with a source of air pressure supply, a ring valve mounted on the spray head and having a tapered groove extending circumferentially and adapted by the circumferential adjustment of the valve to control the communication between said supplemental passages and a source of air supply and the volume of air supplied to said passages.

4. A spray head having supplemental air discharge passages in communication with a source of air pressure supply, and a rotatable ring valve between the source of supply and said passages and having a groove extending part way about the nozzle to open or close the communication between said source of supply and said passages, or to selectively vary the volume of air supplied to the passages, as the valve is turned.

5. A spray head comprising an inner material discharge nozzle, an outer air discharge nozzle having opposed supplemental air jet discharge openings, said outer nozzle being adjustable circumferentially to vary the plane of the supplemental air jets, and means for controlling the volume of air supplied to said jet discharge openings, said means being mounted on said outer nozzle and normally maintaining its relation thereto when the nozzle is adjusted, but adjustable independently thereof to vary the volume of the supplemental jets.

6. A spray head comprising an inner material discharge nozzle, an outer air discharge nozzle having opposed supplemental air jet discharge openings, said outer nozzle being adjustable circumferentially to vary the plane of the supplemental air jets, and a ring valve mounted on said outer nozzle and independently adjustable circumferentially thereof to vary the volume of the supplemental jet discharge, said ring valve normally maintaining its relation to said outer nozzle when the latter is adjusted.

In testimony whereof I have hereunto signed my name to this specification.

GODFREY A. MUELLER.
